UNITED STATES PATENT OFFICE.

CHARLES A. DREISBACH, OF NEW HAVEN, CONNECTICUT.

PULVERIZER.

1,118,846.

Specification of Letters Patent. Patented Nov. 24, 1914.

Application filed July 11, 1913. Serial No. 778,506.

To all whom it may concern:

Be it known that I, CHARLES A. DREISBACH, a citizen of the United States of America, and residing at New Haven, in the county of New Haven and State of Connecticut, have invented a certain new and useful Improvement in Pulverizers, of which the following is a specification.

My invention relates to a pulverizing apparatus and particularly to an apparatus adapted to crush slag cinders for the purpose of recovering therefrom their metal components.

In the accompanying drawings, Figure 1 is a broken front elevation of an apparatus in which my apparatus is embodied in one form; Fig. 2 is a broken section on line 2—2, Fig. 1; Fig. 3 is a section on line 3—3, Fig. 1; Fig. 4 is an elevation of a detail.

In operating blast furnaces prior to casting it is common practice to pour off the slag from the melt onto the floor of the casting chamber. It is impossible to remove the slag in this manner with such nicety that some metal is not carried with it and it has consequently become common practice to gather the slag, grind it and separate the metal from the slag for reuse. The customary apparatus employed for this purpose is a rolling barrel containing a crushing ball or cylinder which rolls freely in the barrel and pulverizes the slag cinder which is dumped in the bottom of the barrel. This action, while sufficiently effective, is very hard on the apparatus that it deflects the material from the placement. In the present construction the crushing of the slag is accomplished by rolls held out of contact with the barrel and to which the slag is fed by the rotation of the latter.

In the form here shown the present apparatus comprises a pair of uprights 10, each carrying a circular head plate 11 forming a stationary barrel end. The barrel 12 is provided with external annular flanges 13 which rest on rollers 14 freely journaled in adjustable bearings 15 mounted on the frame 10. Journaled in the stationary heads 11, I provide a live shaft 16 carrying the central crushing roll 17 which is keyed thereto. Mounted on one end of the latter is a large driving gear wheel 18 which meshes with the pinion 19 keyed to the shaft 20 of the fast and loose pulleys 21. A small pinion 22 on the shaft 16 meshes with an idler 23 which transmits its motion in turn through

the idler 24 to the internal gear 25 on the roll bearing flange 13, at one end of the barrel. It is thus seen that the crushing roll 17 and the barrel 12 are both positively driven from the shaft 16. Coöoperating with the crushing roll 17 I provide two additional crushing rolls 26 and 27 which bear by gravity against the roll 17 and are guided in the slot bearings 28 and 29 respectively on the stationary heads of the barrel.

An opening 30 at one end of the barrel permits the slag cinder to be fed into the interior thereof. I prefer to provide a feed chute 31, pivoted at 32 to the stationary head 11 and retained in the position in Fig. 1 during the feed of slag to the barrel, by the latch 33 on the spindle 34 of the pivoted apron 35. When the cinder is shoveled into the chute 31, it falls to the bottom of the barrel and is carried up by the pallets 36 which discharge by gravity upon the apron 35, the latter being so arranged as to guide the material between the crushing rolls 17 and 26 where it receives its first reduction in diameter and then passes between the rolls 17 and 27 where it receives its second reduction in diameter and falls to the bottom of the barrel. The periphery of the barrel is perforated as at 37 to permit the small particles of crushed slag to pass through into the water trough 38 into which the lower portion of the drum dips. A stream of water from a pipe 39 constantly circulates through the trough 38 and carries off at the overflow 40 the light particles of the cinder mass which have passed through the screen-like periphery of the barrel. The heavy particles of the mass, which contain the metal, sink to the bottom of the trough and may be raked or otherwise suitably withdrawn therefrom at intervals.

When a given quantity of cinder has been sufficiently ground and it is desired to empty the drum of whatever remains therein, the apron 35 is swung over by means of the handle 41 to the position indicated in dotted lines Fig. 3. In this position such material as is brought up by the pallets 36 is deflected not to the rolls 17 and 26, but to the stationary chute 42 within the barrel and over which the apron 35 normally lies. The bottom of this chute is inclined downward and guides the material to the swinging chute 31, which, on the release of the catch 33, swings down by gravity to the position shown in dotted lines in Fig. 1 in which

position it forms a continuation of the stationary chute 42 and such material as is still in the barrel is discharged through the chute 42 and feed chute 31.

5 The operation of the apparatus is easily understood. Upon the shifting of the driving belt to the live pulley 21, pinion 19 is rotated, thereby driving the gear 18 and its shaft 16. This sets in motion not only the 10 crushing roll 17 which is keyed to the shaft, but also the train of gears 22, 23, 24 through which the drum is driven. The rolls 26, 27 are rotated by reason of their frictional contact with the roll 17. As the cinder is 15 fed into the drum through the hopper 31 (now in the position shown in Fig. 1) it is carried up by the pallets 36 and dropped upon the apron 35 which discharges to the crushing rolls. Such material as a single 20 passage through the rolls is not sufficient to reduce to a diameter small enough to pass out through the reticulated periphery of the drum, is carried up by the pallets and again discharged to the crushing roll. The fines 25 entering the trough 38 either sink by gravity to the bottom or are carried out by the overflow at 39. Inasmuch as all the material falls into the water in which the lower portion of the drum dips, the grinding is done 30 wet and the usual dust of the crusher is avoided. To discharge the drum of metal which has been thoroughly cleaned from slag and clinkers, the handle 41 is turned down to throw the apron 35 into such position 35 that it deflects the material from the pallets to the discharge chute 42, the hopper 31 being now in position to form a continuation thereof discharging outside the barrel.

The apparatus may also be used for dry 40 grinding, if preferred, and for such use I may provide a hole 43 in one of the heads to receive a dust flue leading to a suitable exhauster (not shown), by means of which the dust is drawn off as fast as made by the 45 rolls. Again, the rolls 26-27 may be spring-pressed against the live roll 17 instead of bearing against the same solely by gravity. Various other modifications will 50 readily suggest themselves and the construction shown is to be regarded merely as an exemplary embodiment of my invention.

I claim as my invention:—

1. A crushing apparatus of the type described, comprising a rotary barrel, a plurality of crushing rolls in frictional contact with each other arranged within the barrel, a live shaft keyed to one of said rolls the other rolls being idlers, gearing for driving said shaft and gearing between said shaft and barrel for rotating the latter, in combination with means carried on the inner face of the barrel for lifting material from the lower portion of the barrel and feeding the same to the crushing rolls.

65 2. A crushing apparatus of the type de-

scribed, comprising a rotary barrel, a live crushing roll centrally supported within the latter, a pair of idler crushing rolls free to rise above the same and bearing by gravity in frictional contact with said live roll, and means carried on the inner periphery of the barrel for feeding material from the bottom of the drum to the crushing rolls.

3. A crushing apparatus of the type described, comprising a rotary barrel, crushing rolls arranged in the upper portion of the barrel and out of contact with the latter, one end of the barrel being apertured to admit material to the lower portion thereof, means on the inner face of the barrel for lifting said material to the upper portion of the barrel and discharging it to said crushing rolls, a pivoted apron for directing said material to the crushing rolls, a stationary discharge chute normally covered by said apron, and means for swinging said apron to direct to said discharge chute the material lifted by the barrel.

4. A crushing apparatus of the type described, comprising a rotary barrel, crushing rolls arranged in the upper portion of the barrel out of contact with the latter, one end of the barrel being apertured to admit material to the lower portion thereof, means on the inner face of the barrel for lifting said material to the upper portion of the barrel and discharging it to the crushing rolls, a pivoted apron for directing said material to the crushing rolls, a stationary discharge chute normally covered by said apron, and means for swinging said apron to direct to said discharge chute the material lifted by the barrel, together with a pivoted feed chute directing the material through the aperture in the end of the barrel during the feed to the latter and adapted to be swung into the barrel to coöperate with the stationary discharge chute therein to lead material from the barrel, substantially as described.

5. In crushing apparatus of the type described, a rotary barrel apertured at one end to admit material to the interior thereof, a pivoted feed chute for feeding material through said aperture, means on the inner periphery of the barrel for lifting the material, crushing rolls within the barrel, a pivoted apron for guiding said lifted material to the rolls, a stationary discharge chute within the barrel and means for swinging said apron and feed chute on their pivots to respectively direct lifted material to and receive the same from said stationary discharge chute, substantially as described.

6. A crushing apparatus of the type described, comprising a rotary barrel, a crushing roll axially arranged therein, means for positively rotating said roll, an idler crush-

ing roll resting upon said driven roll and free to rise therefrom, the axis of said idler roll being arranged to one side of a plane passing vertically through the axis of the driven roll, an apron arranged on the other side of said axis and serving to direct material to the bite of the said rolls, means for lifting material from the bottom of the barrel and discharging the same upon said 10 apron together with means to rotate the barrel.

7. A crushing apparatus of the type described, comprising a rotary barrel, a crushing roll axially arranged therein, means for 15 positively rotating said roll, a plurality of idler crushing rolls resting against said driven roll and free to rise therefrom, the axes of said idlers being arranged to one side of a plane passing vertically through 20 the axis of the driven roll, an apron arranged on the other side of said axis and

serving to direct material to the bite of said rolls, means for lifting material from the bottom of the barrel and discharging the same upon said apron, together with means 25 to rotate the barrel.

8. A crushing apparatus comprising a rotary barrel apertured to admit a charge to the bottom thereof, crushing rolls arranged within the barrel, means for lifting the 30 charge from the bottom of the barrel, and means within the barrel for either directing the lifted material to the crushing rolls or discharging it from the barrel.

In testimony whereof I have signed my 35 name to this specification, in the presence of two subscribing witnesses.
